CENTRIFUGAL MACHINE

Wilmer H. Bath, West Conshohocken, Pa., assignor to The Sharples Specialty Company, Philadelphia, Pa., a corporation of Delaware

Application February 27, 1935, Serial No. 8,459

2 Claims. (Cl. 233—47)

The present invention relates to the art of the centrifugal treatment of fluid substances. It is particularly concerned with improvements in the class of centrifugal machines in which a concentration of suspended solid materials within a liquid occurs during the feed of a suspension of solids in liquid to the rotor of the machine and the concentrated suspension is discharged thereafter intermittently from the machine by breaking the connection between two normally abutting portions of the machine to afford a discharge outlet for the suspension.

A centrifugal separator of this general type is disclosed in the patent to Nyrop 1,735,692 and the present invention was conceived as a solution of problems encountered in the application to commercial uses of machines of the general type of those forming the subject matter of the Nyrop patent. In the Nyrop invention of that patent, a centrifugal rotor is illustrated which is formed in two parts, which are axially separable to afford provision for intermittent peripheral discharge of a concentrated effluent from the rotor. In the use of a machine of this type, it is necessary, in order to prevent leakage, to provide a sealing member between the abutting axial separable portions which control the intermittent discharge. Such sealing members are subjected to very severe erosion effects by reason of the impingement of material thereagainst incident to its discharge. Therefore, the sealing members applied to this use have, in many cases, required replacement after a few hours use. Furthermore, I have found that the replacement of the sealing means has become necessary not because the sealing material has become uniformly worn, but because of severe local deterioration. I have therefore concluded that if a satisfactory deformable sealing material can be found and used under conditions to bring the internal pressure of the bowl to apply to the sealing means for effecting a perfect joint, that these local deteriorations can be overcome to a large degree and that the life of the sealing material will be greatly prolonged. It is therefore to the solution of this problem to which I have addressed myself.

Further objects of the invention and the manner in which they have been attained will be in part pointed out hereinafter and will be in part obvious from a reading of the subjoined specification in the light of the attached drawing, in which:

Fig. 1 is a central axial sectional view through

a centrifugal separator bowl illustrating the application of my invention;

Fig. 2 is an enlarged detail view of the separable peripheral portion of the bowl, and

Fig. 3 is a modified form of my invention embodying, however, the same principles of operation.

Referring now more particularly to the drawing in which like reference numerals indicate like parts, the separator bowl comprises generally a 10 rotatable section 10 and a second section 12 which may be termed the bowl cover which is likewise rotatable but axially movable with respect to lower bowl section 10. A driven shaft 14 is provided and fixed within a boss 16 of the 15 inner lower bowl section 18. The inner lower bowl section 18 and the bowl cover 12 are attached in a suitable manner, so as to, in effect, constitute a unit which is adapted to rotate and to move axially as one. It is to be understood, 20 of course, that the whole bowl including the outer lower bowl member 10, the inner lower bowl member 18, and the cover member 12 partake of the same rotary movement imparted by the shaft 14.

The interior of the bowl tapers from both ends toward the middle and has its maximum interior diameter at the zone of junction between its opposed portions 12 and 18 and provided in that neighborhood are peripheral openings 20 which 30 are adapted to discharge solid material when the discharge opening has been opened by a relative movement of the parts 12 and 18 with respect to the outer lower bowl portion 10. The movement of the bowl members 12 and 18 in an axial direction is accomplished by hydrostatic pressure developed under the inner lower bowl member 18 by the admission of liquid from a nozzle 22, which liquid finds its way through a channel 24 and into a space 26 under the lower inner bowl member 18. 40 Suitable means, hereinafter described, have been provided for preventing the leakage of liquid between the outer lower bowl member 10 and the inner lower bowl member 18.

The axially movable bowl members are re- 45 turned to their lower position by means of a plurality of spring members, one of which is shown, at 28. As shown, the spring member 28 surrounds a bolt 30 which projects downwardly from the lower inner bowl member 18 through a 50 suitable opening in the base of the lower outer bowl member 10. One end of the spring 28 bears against the exterior of the lower outer bowl member 10 while the other end of the spring is retained by means of a nut 32 screw threaded to 55

the outer end of the bolt 30. Thus upon a raising of the bowl members 12 and 18 by hydrostatic pressure as hereinbefore mentioned, the spring 28 is compressed and upon the release of the hydrostatic pressure, the tension of the spring 28 will return the bowl members 12 and 18 to their lower position thus closing the discharge openings.

Material to be treated may be admitted through a distributing feed tube 34 to be discharged into the bottom of the bowl. Disc inset 36 of usual construction is illustrated and accelerating wings 38 of usual construction are provided. Upon rotation of the bowl, the solid material is forced to the outer portion of the bowl by centrifugal force in the well known manner, while lighter effluent finds its way upwardly near the axis of the bowl and is discharged through discharge ports 40.

20 Axially movable bowl members 12 and 18 are guided in their movement by means of locating pins 42 fixed in the lower outer bowl member 10 and adapted to move in guideways 44 provided in the upper bowl member 12. To guard the locating pins 42 against excessive erosion and to prevent sludge from entering the guideways 44, I have provided replaceable guard sleeves 46 of wear resisting material which surround the pins.

The particular bowl sealing means which 30 forms the subject matter of this invention will now be described. The upper bowl member 12 is provided with a stepped circumferential groove 48 on its inner surface which groove is adapted to receive a sealing gasket 50. The sealing gasket 50 is constructed of any suitable deformable sealing material and I have found that rubber or a composition thereof is satisfactory for this purpose. The sealing member 50 is held in place by two sealing rings 52 and 54. After the sealing member 50 which, as may appear obvious is a relatively slender annular ring conforming to the inner contour of bowl cover 12, is placed in position, a retaining ring 52 may be fixed to the bowl cover 12 in any suitable manner. 40 Thereafter, an annular inner retaining ring 54 is placed in position and fixed to the upper bowl member 12 by means of bolts, one of which is shown at 56. It will be noted that the retaining ring 52 is coextensive with the outer surface of sealing member 50, but that retaining ring 54 is not coextensive with the inner surface of the sealing member 50 but permits a small area at the lower edge of the same to be exposed for a purpose which will hereinafter be more fully described.

55 A second sealing member 60, similar in construction to the sealing member 50, is provided in the inner peripheral edge of the lower outer bowl member 10. The sealing member 60 is held in position by means of a retaining ring 62 fixed to the upper peripheral edge of bowl member 10 and a bowl lining member 64 on the interior of the lower outer bowl member 10. It will be noted that the liner 64 is beveled at its upper edge 66 and extends beyond the upper tapered edge of the relatively movable inner lower bowl member 18. This construction is provided to protect the sealing member 60 from the erosive effect of solids which may be caught between the liner 64 and the inner lower bowl member 18. Furthermore, the liner 64 exposes but a small portion of the inner surface of annular sealing member 60 and this surface is substantially equal to the exposed inner surface of the annular sealing member 50 for a purpose to be hereinafter de-

scribed. At the same time it will be noted that the inner edges of the retaining rings 52 and 62 are in abutting relation and form a continuous solid support for sealing members 50 and 60 respectively when the bowl members are in closed 5 position.

In the operation of this form of the invention, during rotation of the bowl in the operation of centrifugal separation, a pressure is created at the outer edge of the bowl and this pressure effectively operates to "cold flow" the deformable material of the sealing members 50 and 60 into each other to form an absolutely tight seal irrespective of any irregularities which may be presented in the abutting edges of these seals and 15 irrespective of local erosion. The pressure acting upon these sealing members is sufficiently great to bulge the same into accurate sealing contact as shown at 68 in Fig. 2.

20 In describing the modified form of the invention shown in Fig. 3, I will use the same reference numerals used to describe the first embodiment of the invention wherever applicable, but with the addition thereto of 100. In this form of the invention, I have shown a fragment of the 25 lower outer bowl member 110, the inner lower bowl member 118, and the bowl cover 112. In this form of the invention, the bowl members 112 and 118 move axially with respect to the lower outer bowl member 110 and in this form of the 30 invention, I have provided a single sealing member 150 which is positioned in a recess in the bowl cover 112 and which is held in place by an annular retaining ring 154 fixed to the upper bowl member 112 by means of screws 156. The lower 35 bowl member 110 is provided with a projecting annular lip 162 which is adapted to rest in abutting relation with the exposed face of the sealing member 150. In this form of the invention the sealing member 150 is in part protected from 40 erosion by means of the retaining ring 154 which extends to the plane of the lower edge of the cover member 112 at the point where the same contacts the exposed edge of the sealing member 150. Thus the lower edge of the cover 112, 45 the exposed edge of the sealing member 150 and a portion of the retaining ring 154 lie in substantially the same horizontal plane so that the discharge of solids over the exposed surface of the sealing member 150 is materially prevented from 50 cutting the sealing member 150. However, erosion nevertheless takes place and to overcome the effects of local erosion and to insure a perfect seal between the annular projection 162 of the lower bowl member 110 and the exposed and 55 abutting portion of the sealing member 150, I have provided a novel means for utilizing the pressure within the bowl for forcing the sealing member 150 into tight contact with projection 162.

60 Bowl cover 112 is provided with an annular chamber 170 above the sealing member 150 and this chamber communicates by way of a plurality of channels 172 with ports 174 in the retaining ring 154 and thus with the pressure 65 within the bowl. In its closed position the sealing member 150 will therefore be carried into tight sealing contact with projection 162 whenever the bowl is operated and it follows therefore that the greater the tendency for leakage by 70 virtue of increasing pressure within the bowl, the greater will be the sealing effect of the sealing member 150. This function is assisted by the fact that the area of the sealing member 150 which is exposed to pressure in the chamber 75

170 is greater than the area which may be exposed to bowl pressure at the joint between the sealing member 150 and the bowl projection 162. Furthermore, the chamber 170 is a greater radial distance from the axis of rotation than the inner exposed edge of the joint between the sealing member 150 and the bowl projection 162 and, therefore, is subjected to a greater pressure.

I have provided means for sealing the space 10 between the lower bowl liner 64 and the lower inner bowl member 18 which comprises two annular flanged rings 80 and 82 which are held in a circumferential groove in the lower inner bowl member 18 and in spaced relation by a spacing 15 ring 84. The flanged rings 80 and 82 are made of relatively flexible metal and to the vertical flanged portion of the ring 82 is fixed a lead weight 86 which is adapted to carry the vertical flanged portion of this ring into sealing contact 20 with the liner 64 under centrifugal force. I have found in the operation of these machines that under some conditions of operation, a metal to metal seal is not entirely satisfactory, and I have therefore provided the vertical flange of the ring 25 80 with an extension of flexible fabric 88 which is held between the ring 80 and a lead supporting and weighting member 90 so that the fabric is carried into perfect contact with the liner 64, thus providing a seal in which the metal to metal contact is supplemented by the action of the flexible fabric which has a greater capacity for conforming to the contour of the liner 64 and which also has the peculiar characteristic of retaining an applied lubricant to a greater degree.

30 In this specification I have described what I now consider the preferred embodiments of the invention, but it is to be understood that the invention is not limited to the particular forms shown, because it may be embodied in other forms, 35 and it is also to be understood that in the following claims it is my desire to cover the invention in whatever form it may be embodied.

40 What I claim as my invention is:

1. In a centrifugal machine, the combination 45 comprising a centrifugal rotor and means for feeding to said rotor a fluid material adapted to be subjected to centrifugal treatment, said rotor including a separating chamber, a pair of separable portions extending annularly about the 50 axis of the rotor and mounted to be movable relative to each other only in an axial direction

and normally retained in abutting relationship to prevent the discharge of material from said chamber, means for separating said portions to afford provision for discharge of material from said chamber, and means for sealing said chamber against discharge of material between said portions when in abutting relationship, said means comprising annular abutting sealing members carried in the periphery of and positively attached to said separable portions and maintained therein by portions of said separable members on the outside surface of said sealing means coextensive with the length of said deformable members providing a support therefor throughout their entire length and noncoextensive retaining means on each of said separable portions within said chamber, the ends of the non-coextensive portions being spaced from the line of separation between said portions whereby said sealing members are held against lateral deflection and carried into tight sealing engagement by pressure within said chamber, the abutting surfaces of said sealing members terminating in the radial plane containing the free edges of the rotor portions when in abutting relation.

2. In a centrifugal machine, the combination comprising a centrifugal rotor having a separating chamber defined by a base portion and a cover portion extending annularly about the axis of the rotor and mounted to be movable relative to each other only in an axial direction and normally retained in abutting relationship to prevent the discharge of material from said chamber, means for separating said portions to afford provision for discharge of material from said chamber, a deformable sealing member positively attached to each of said base and cover portions of said rotor and having one entire surface in contact with a rigid part of said portions at the line of separation therebetween for sealing said chamber against the discharge of material between said portions when in abutting relationship, a second surface of said sealing members being exposed to the pressure within said rotor by means of which the same are distorted into sealing engagement, the abutting surfaces of said sealing members terminating in the radial plane containing the free edges of the rotor portions when in abutting relation.
